(57) **CLAIM**

The ornamental design for a cockpit cover, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and right side perspective view of a cockpit cover showing the new design.

FIG. 2 is a front view thereof.

FIG. 3 is a left side view thereof.

FIG. 4 is a right side view thereof.

FIG. 5 is a top view thereof; and,

FIG. 6 is a front, top and left side perspective view thereof. Any portion of the cockpit cover not shown in the figures forms no part of the claimed design.

The color shown in the figures depicts a portion of the cockpit cover that forms part of the claimed design.
